A. PERRI.
SHOE HEELING METHOD.
APPLICATION FILED APR. 10, 1919.

1,345,023.

Patented June 29, 1920.

UNITED STATES PATENT OFFICE.

ANGELO PERRI, OF WATERTOWN, MASSACHUSETTS, ASSIGNOR TO REECE SHOE MACHINERY COMPANY, OF BOSTON, MASSACHUSETTS, A CORPORATION OF MAINE.

SHOE-HEELING METHOD.

1,345,023.

Specification of Letters Patent. Patented June 29, 1920.

Original application filed November 11, 1918, Serial No. 262,104. Divided and this application filed April 10, 1919. Serial No. 290,605.

To all whom it may concern:

Be it known that I, ANGELO PERRI, a citizen of the United States, residing at Watertown, in the county of Middlesex and State of Massachusetts, have invented certain new and useful Improvements in Shoe-Heeling Methods, of which the following is a specification, reference being had therein to the accompanying drawing.

10 This invention is an improved shoe heel- ing method. In part the present invention embodies a method and produces a product similar to my prior Patent 1,289,054, patented December 24, 1918, and in part is an improvement thereover. The general ob- 15 ject of the present invention therefore is to improve the method of preparing and at- taching heels to shoes. The more particular objects and advantages will be made clear 20 in the hereinafter following description of one illustrative embodiment of the invention, or will be apparent to those skilled in the art. To the attainment of such objects and advantages, the present invention con- 25 sists in the novel features of method, steps, operations and details hereinafter described, illustrated or claimed.

This application is a division of my prior application Serial No. 262,104, filed November 11, 1918, for heel nailing machine, this application referring more particularly to the method and the prior one to the machine and mechanism, to which a reference is hereby made for a more full disclosure 35 of the preferred mode of carrying out the present invention.

In the accompanying drawings, which were originally filed as Figures 12 to 20, in- 40 clusive, of my patent application Serial No. 262,104, Fig. 1 is a side elevation of a built- up heel in the rough.

Fig. 2 is a similar view, partly broken away, of the same heel after its vertical compression, and the concave shaping of the 45 lower surface or seat thereof.

Fig. 3 is a similar view of the same heel, partly broken away, showing the piercing of a series of short-depth nail holes in a diverging manner.

50 Fig. 4 is a top plan view of the heel at the stage of the process shown in Fig. 3 but with the piercing awls extracted.

Fig. 5 shows the succeeding stage, in which

a series of nails has been inserted and partly driven while guided by a tapered guide. 55

Fig. 6 shows, in side elevation again, the subsequent extraction of the tapered guide and the bending of the nails into straight- up parallel positions.

Fig. 7 shows the heel subsequently ap- 60 plied to the shoe and the nails further driven and clenched.

Fig. 8 shows a top lift driven into place on the parallel nail tops.

Fig. 9 shows a top view of the completely 65 attached and finished heel after the pre- ceding steps and the trimming.

As in said prior patent, this application shows a shoe heel- ing method comprising driving a series or group of nails diverg- 70 ingly into the heel and leaving the con- verging nail tops outstanding slightly, and bending them into substantial parallelism before forcing a top lift into place upon said nail tops. In the prior patent, the 75 straightening of the nail tops into parallelism was performed subsequently to the attachment of the heel to the shoe. In this respect the present invention is an improve- 80 ment in that the bending is performed before the heel is applied, and this enables certain operations which are of additional advantage.

I will now recite more fully the steps in- 85 volved in the present improvement. Each heel after being properly compressed and shaped, is preferably first pierced to form a series of tapering holes in proper position to receive the nails. Then, unlike said prior patent, I prefer to place against the heel 90 and between the pierced holes a tapering guide or cone which is to guide the nails as they are driven. Preferably, the nails are not engaged with the tapering guide until after the latter is in engagement with 95 the heel. Next, the nails are driven into the heel nearly to the point of emerging at the base. At this point I spread or straighten up the nails by bending into parallelism. This is enabled to be readily done by simply 100 drawing or lifting off the tapering guide or cone, the base of which wedges apart the nails as desired. The usual heel nails are not springy and retain their bent position.

A flat guide plate or die may now be laid 105 inside the group of nail tops and the heel

laid against the shoe, and the nails then driven and clenched interiorly, leaving the slightly projecting and parallel nail tops, upon which subsequently the top lift is 5 forced or drawn, usually after an application of cement beneath the top lift.

Preferably the compressing, the piercing, the inserting of the nails, the partial driving of them, and their bending into parallelism 10 are performed in a single machine, and in said parent application is disclosed and claimed a machine which performs each of, and coöperates in all of, these operations. After such operations the heel is preferably 15 removed and joined with the shoe and the top lift.

Describing the method, Fig. 1 is a side elevation of a built-up heel 20 in the rough. The top lift 21 is not yet applied, but is seen 20 in subsequent Figs. 8 and 9. Preferably the first operation on the rough heel 20 is its vertical compression, in which the entire heel is reduced in height and the base, or what will be termed the underneath side, is 25 concavely shaped to form the surface or heel seat 22, as shown in Fig. 2, and adapted to fit the shoe sole. As shown in Fig. 3, a series of short-depth nail holes 23 are next 30 divergently pierced by awls 24 at the top side of the heel. After the removal of the awls the heel will appear as seen in top view, Fig. 4. Next, a series of nails 25 is inserted and driven by drivers acting in the direction of the arrow 26, Fig. 5. The nails 35 are driven not so far as to emerge at the base but so as to leave protruding nail tops 32. According to this invention, the space 40 between the series of diverging nails is preferably occupied by a tapering guide 27, the effective surface of which is preferably cone-shaped. Preferably the nail tops 32 are bent into the straight-up positions shown at 33 at this stage of the process, rather than after attachment to the shoe, 45 and the step is indicated in Fig. 6 as performed by the lifting of the guide 27, thus causing the separating and straightening of the nail tops, as stated. The heel may now be detached from the machine and applied 50 to the shoe elsewhere by driving means acting in the direction of the arrows 28, Fig. 7,

which serves to force the nails into and through the shoe outsole 29 and insole 30, where the nail ends will be suitably clenched at 31. Preferably during this operation the 55 nail tops 33 will be maintained straight and upright by a die 35 placed within the series of nails for that purpose. Thereafter, as seen in Fig. 8, the top lift 21 is to be laid in place and driven upon the short 60 nail tops 33 by suitable hammer or driver 36. Fig. 9 shows in top view the final relation to the shoe of the heel, the top lift and the nails. After attachment, the heel, as usual, may be trimmed to form, as indicated by the dotted form line 34, Fig. 8. 65

The shoe, or product, whose manufacture has thus been described, comprises a heel substantially smaller at the top than at the base, and secured to the shoe by a series of attaching nails having a diverging arrangement, so that the attaching points are spaced or arranged over a much larger circumference or area than the points at which the 70 nails are driven through the small or top 75 end of the heel.

It will thus be seen that I have described a shoe heelng method embodying the principles and attaining the purposes of the present invention. Since many matters of 80 arrangement, procedure, order of steps, details, and other features may be variously modified without departing from the underlying principles, it is not intended to restrict the invention to such features except 85 in so far as specified in the appended claims.

What is claimed is:

1. A shoe heelng method comprising driving a series of nails divergently into the heel top, leaving the nail ends outstanding, bending them into substantial parallelism, driving the nails further to enter the shoe, leaving the nail ends slightly outstanding, and forcing a top lift upon said nail ends. 90

2. A method as in claim 1 and wherein 95 during the second recited driving the series of nails is interiorly supported to retain their substantial parallelism.

In testimony whereof I have affixed my signature hereto.

ANGELO PERRI.
